UNITED STATES PATENT OFFICE.

RUDOLPH W. SCHULZ, OF WATERLOO, IOWA.

RAILWAY-TIE.

1,086,091.

Specification of Letters Patent.

Patented Feb. 3, 1914.

Application filed May 28, 1913. Serial No. 770,374.

To all whom it may concern:

Be it known that I, RUDOLPH W. SCHULZ, a citizen of the United States of America, and a resident of Waterloo, Blackhawk county, Iowa, have invented certain new and useful Improvements in Railway-Ties, of which the following is a specification.

My invention relates to improvements in railway ties, and the object of my improvement is to provide an all metallic cross-tie for railway rails adapted for secure emplacement in the road bed, and provided with detachable securing-means for the rails. This object I have accomplished by the means which are hereinafter described and claimed, and which are illustrated in the accompanying drawings, in which:

Figure 1 is an upper plan view of my improved railway tie, with dotted lines representing the positions of the rails when secured thereon. Fig. 2 is a medial longitudinal vertical section in part, and a side elevation in part of my said improved railway tie. Fig. 3 is an enlarged medial vertical longitudinal section of my said tie, comprising only the left-hand portion thereof, the rest being broken away. Fig. 4 is a transverse vertical section of my said tie, with a part broken away, taken through the box-casing on the under side of the tie.

Similar numerals of reference denote corresponding parts throughout the several views.

The body 14 of my tie comprises a flat horizontal plate having downwardly obliquely depressed edges 1, to form a reversed trough-shaped body, which may be embedded in the soil or the ballast of the road-bed to securely hold it transversely to the spaced rails 18. Like engaging-devices are located on opposite ends of the plate 14 and placed thereon in a like manner, as is best shown in said Fig. 1. To hold one side of the base of a rail 18, a pair of integral tongues 2 are punched out of said plate 14 and spaced therefrom upwardly as shown.

Referring now to Figs. 3 and 4, the numeral 3 denotes an oblong opening in the plate 14, and the numeral 15 denotes a depending casing-box secured on the under face of said plate spaced from and covering said opening. The opposite longitudinal sides of said box 15 as also one of the longitudinal sloping parts 1, of the tie body, are orificed in line with each other to receive therethrough a rock-shaft

10, with opening 17 in the part 1, being enlarged and the outer end of said shaft 10 being squared to take a removable box-wrench 16. A shaft 10 has within the casing 15 a radial projecting arm or blade 11. Upon the top of the plate 14 is secured a bearing body 13 adapted to receive the oppositely directed studs 12 on one end of the swinging block 7, the latter provided with a downward projection adapted to extend into the opening 3 below the lower surface of the plate 14, and having a transverse groove 8 just below the level of said plate 14. The numeral 4 denotes a clutch-block, 70 whose upper pronged part is adapted to be engaged with the opposite side of the base of the rail 18, with a lower pronged part 6 lying under the plate 14 to engage its lower surface when said block has been seated in the opening 3. Said block 4 has transversely extending lugs 5 adapted to act as stops in bearing against the upper surface of said plate 14 and the abutting faces of the blocks 4 and 7 are formed in a sloping 80 manner, so that when the block 4 has first been seated in said opening 3, with the block 7 swung upwardly, the block 7 may then be swung downwardly to detachably engage the other block, as shown in Fig. 3. The numeral 9 denotes a bent plate-spring, one end of which is secured to the underface of the downwardly projecting part of the block 7, the other part of the spring being bent obliquely upward past the rock-shaft 10, with 90 its extremity bent over in the same general direction as its secured end, and lying adjacent to the opening of the slot 8. To secure a rail, 18, to said tie, the box-wrench 16 is fitted on the squared end of the shaft 10, and the shaft turned in such a manner as to cause its blade 11 to engage the free end of the spring 9 and push the free extremity of the latter into the slot 8 of the block 7, when said block may then be swung upwardly and disengaged from the block 4, the spring 9 sliding by the edge of the opening 3. The block 4 may then be slid along said opening to permit of the rail 18 being located to have one side of its base engaged with the tongues 2. The block 4 may then be pushed back to its former position, to engage the opposite side of the rail base, as shown in Fig. 2, and the block 7 then swung downwardly to cause its projection to enter the said opening, so that when the spring 9 has passed below the level of the under

surface of the plate 14, it will re-act and spring back to engage the under surface of said plate, thus locking said blocks in their first positions, as shown in Fig. 3. A rail 5 may be disconnected from the tie by reversing said process.

This invention forms a quickly operated and convenient means for securing rails in metallic cross-ties, and it is to be understood that details of construction, as shown, 10 may be varied considerably without departing from the scope and principle of my invention.

Having described my invention, what I 15 claim as new, and desire to secure by Letters Patent, is:

1. A railway-tie, comprising a downwardly-troughed body having at its opposite ends like rail-securing means, each rail-securing means including longitudinally-spaced clutch-members adapted to grasp opposite sides of the rail detachably, one of 20 said securing-means being fixed and the other movable to and from the rail, and 25 means for detachably locking said movable means against said rail, comprising a swing-block mounted on said troughed-body to be swung toward and engage the said detachable securing-means when the latter is engaged with the rail, and a yieldable resilient stop for detachably securing said swing-block to the troughed-body while in its said engaged position.

2. A railway-tie, comprising a downwardly-troughed body having at its opposite ends like rail-securing means, each rail-securing means including longitudinally-spaced clutch-members adapted to grasp opposite sides of the rail detachably, one of 30 said securing-means being fixed and the other movable to and from the rail, said troughed body being slotted and the latter securing-means being slidably seated in said slot to be engaged detachably with the under 35 surface of the body when engaging the rail, a swing-block pivoted at one end to the upper surface of said troughed body and having on its other end a slotted projection adapted to be swung into the said first mentioned slot to engage and hold the said securing-means in its engaged position with the rail, a spring secured to the projection on the swing-block and bent upwardly and then reversely to have its free end opposite the 45 slot in said projection and to spring out of said slot to engage the under surface of the troughed-body when the projection is in its 50 said lowered position, and means for mov-

ing said spring-end into the slot in the swing-block projection, to permit the latter 60 to be swung upwardly and release said detachable securing-means from the rail.

3. A railway-tie, comprising a plate having its edges bent downwardly obliquely outward to form an inverted dished body, 65 like securing-means for rails on opposite ends of said plate, each securing-means consisting of fixed tongues projected from the plate toward and adapted to grasp one side of the rail-base, said plate having a slotted 70 opening near and spaced from said tongues longitudinally, a casing-box secured on the under face of said plate below said opening and having aligned bearing-orifices in its opposite longitudinal sides, the adjacent depressed longitudinal edge of said plate having an orifice in line with such other orifices, a rock-shaft seated in all three of said orifices to project without the tie, said shaft having a longitudinally-arranged fin within 80 said box, a clutch-block slidably seated in and occupying only a part of the slotted opening in said plate and having spaced projections above and below the plate, with the upper projection adapted to grasp the 85 opposite side of the said rail-base when moved toward it, and the lower projection contacting with the under surface of the plate, the opposite end of said block being sloped toward the rail upwardly, a swing-block having one end pivoted to the top of 90 said plate and having an integral depending projection on its other end, said other end being sloped to fit upon the abutting sloping end of said clutch-block when moved down to contact therewith, the projection of 95 the swing-block being movable into the slotted opening in said plate and having a transverse slot below the level of said opening when in that position, a plate-spring secured to the lower face of said projection, then bent upwardly toward said rock-shaft and then having its free end bent toward the slot in the projection, said shaft when rocked being adapted to move its said fin against 100 said spring to push its bent over end into the slot in the projection, to free the spring-end from the under surface of the plate with which it is normally engaged.

Signed at Waterloo, Iowa, this 15th day 110 of May 1913.

RUDOLPH W. SCHULZ.
